(57) CLAIM

The ornamental design for a scrubber towel as shown and described.

DESCRIPTION

FIG. 1 is a front view of a scrubber towel according to the present design;

FIG. 2 is an enlarged partial view taken from the portion indicated 2 in FIG. 1;

FIG. 3 is an enlarged partial view taken from the portion indicated 3 in FIG. 1;

FIG. 4 is a back view of the scrubber towel;

FIG. 5 is an enlarged partial view taken from the portion indicated 5 in FIG. 4;

FIG. 6 is a right side view of the scrubber towel;

FIG. 7 is an enlarged partial view taken from the portion indicated 7 in FIG. 6;

FIG. 8 is an enlarged partial view taken from the portion indicated 8 in FIG. 6;

FIG. 9 is a bottom view of the scrubber towel;

FIG. 10 is an enlarged partial view taken from the portion indicated 10 in FIG. 9;

FIG. 11 is an enlarged partial view taken from the portion indicated 11 in FIG. 9;

FIG. 12 is a front perspective view of the scrubber towel;

FIG. 13 is an enlarged partial view taken from the portion indicated 13 in FIG. 12;

FIG. 14 is an enlarged partial view taken from the portion indicated 14 in FIG. 12;

FIG. 15 is a back perspective view of the scrubber towel; and,

FIG. 16 is an enlarged partial view taken from the portion indicated 16 in FIG. 15.

The broken line showing of the scrubber towel is for the purpose of illustrating portions of the scrubber towel which form no part of the claimed design.
